The ornamental design for a grille for mounting onto the license plate holder in the front bumper of an automobile, as shown and described.

DESCRIPTION

FIG. 1 is a perspective view of a grille for mounting onto the license plate holder in the front bumper of an automobile showing my new design;

FIG. 2 is a rear elevational view thereof;

FIG. 3 is a top plan view thereof;

FIG. 4 is a side elevational view thereof; and

FIG. 5 is a front perspective view of a grille for mounting onto the license plate holder in the front bumper of an automobile showing a second embodiment of my new design, it being understood that the rear is substantially flat and unornamented.
